COMPOSITE PACKAGE

Charles C. Adams, New York, N. Y., assignor to
 Davis & Geck, Inc., Brooklyn, N. Y., a corpora-
 tion of New York

Application October 8, 1948, Serial No. 53,440

1 Claim. (Cl. 206—63.3)

1

The present invention relates to a composite package which shall include a sterile surgical article such as a suture or the like.

The principal object of the invention is the provision of such a package which is convenient to handle both from the standpoint of the surgeon and his nurse assistants, which insures the maintenance of sterility of the surgical articles contained therein, which has a minimum of manufacturing difficulties including cost, and which is so constructed as to minimize damage and breakage if accidentally dropped.

These and other objects are accomplished by providing a composite package in which the surgical articles such as sutures are placed in more or less rigid containers, the containers placed within an inner, substantially transparent envelope with a quantity of sterilizing fluid, the inner envelope then sealed, placed within a similar outer envelope with more sterilizing fluid and the outer envelope sealed.

It is to be understood, of course, that the immediate container for the surgical article and the envelopes are sufficiently resistant to the sterilizing fluid used, such as ethyl alcohol and the like, to prevent leakage or evaporation.

Throughout the specification and claim where the word "transparent" is used, it is to be understood that this term means either transparent or translucent to such an extent that any indicia included on or within the surgical-article-container will be visible through the walls of the outer envelope.

Any of the polyethylene plastics is admirably suited for this purpose as they have the property of reasonable transparency, flexibility, toughness, are resistant to most sterilizing fluids including ethyl alcohol, can readily be made in seamless, tubular shapes which may then be cut to desired lengths and the ends heat-sealed with or without folding, or any of the well known plastic cements may be used to assist in this operation.

The invention contemplates that the amount of sterilizing liquid placed in the inner envelope and in the outer envelope will be less than the possible capacity of each envelope. It is also contemplated that at least some air space may remain above the liquid level in the envelopes so that there will be no tendency for the envelopes to balloon and thus accidentally rupture in case a series of such packages are placed together or put under some pressure as by handling.

It has been found that such a package has the unexpected property of resisting rupture and affording maximum protection to the surgical-

2

article-containers when dropped due to the fact that the envelopes are only partially filled with liquid. When dropped, the surge of liquid within the individual envelopes tends to cushion the fall and this is accentuated by the fact that the envelopes are of a flexible nature.

Other objects and advantages will appear as the description proceeds and with reference to the following drawings in which:

10 Fig. 1 is a perspective view of a composite package of the invention;

Fig. 2 is a sectional view along the line 2—2 of Fig. 1;

Fig. 3 is a perspective view of a method of assembly.

Referring now with particularity to the embodiment illustrated in the drawings, a well known type of suture container is shown at 1 which comprises a length of glass tubing sealed at each end, within which has been placed a length of suture material 2 and which also carries indicia 3 which may indicate the length, grade, size, manufacturer's name, etc. The tube 1 may or may not contain a quantity of sterilizing liquid 4 as is well known.

In the preferred form, one or more of these suture tubes are placed in a flexible, substantially transparent, sterilizing liquid-resistant-envelope 5 of a polyethylene plastic or the like. Such envelope can conveniently be made from a length of seamless tubing to minimize rupture. Also within the inner envelope 5 is placed a quantity of sterilizing liquid 6 of a volume less than the possible inner volume of the envelope. The envelope is then partially collapsed so as to remove at least a portion of the air above the liquid level therein and either heat-sealed or sealed with any of the well known plastic cements which is also insoluble in the sterilizing liquid used. In most cases, the sterilizing liquid used throughout the package may be any of the well known substances such as ethyl alcohol or the like.

The inner envelope 5 carrying the suture containers is then placed in an outer envelope 7 similar in all respects to the inner envelope 5 except slightly larger to accommodate the inner envelope and its contents. Additional sterilizing liquid 8 is then placed in the outer envelope and the envelope sealed as before. It is preferable that there be a reasonable amount of space between one sealed end of the inner envelope and the corresponding sealed end of the outer envelope to enable the nurse or doctor to cut the edge portion of the outer envelope without damaging the inner one.

In use, the circulating nurse (unsterile)

chooses a package of sutures appropriate for the occasion, that is, as to size, grade, color and number of sutures contained in the package, and with her scissors or other instrument cuts off the top edge being careful not to mutilate the inner envelope. Holding onto the uncut edge of the outer envelope 7, she permits the inner envelope and the contained liquid to either fall upon a sterile towel from which it can be removed by the sterile nurse who usually wears rubber gloves or to move the inner envelope out of the outer one a sufficient distance to let the sterile nurse grasp it and remove it therefrom.

It is to be noted at this point that the circulating nurse has had no occasion to touch the inner envelope which because of its contained sterilizing liquid is completely sterile on the outside.

The sterile nurse then has in her hands a package which is sterile both on the inside and the outside. She then cuts the end portion of the inner envelope 5, selects the suture tube desired and removes the suture for the doctor in the usual manner such as by breaking the tube.

It is to be noted that the only thing unsterile about the entire composite package is the outside of the outer envelope so that as the inner envelope, the suture containers and the sutures are sequentially removed, they are in a completely sterile condition both inside and out, and no opportunity for contamination exists.

Attention is also called to the fact that as both envelopes are substantially transparent, the nurse is readily able to read the indicia on or within the suture container so that she may readily choose the type of suture required.

The fact that there is sterilizing liquid in both the inner and outer envelopes also insures quick and ready detection as to whether or not there is a leak of that liquid which might lead to infection and the package rejected.

It is also of considerable advantage to be able to make available to the doctor a plurality of sutures in one composite package without the necessity of handling more than one package.

It has been found that such a composite package is of particular advantage in that not only does the fact that the two envelopes are flexible help to prevent breakage of the glass or other rigid innermost container for the sutures if the package is accidentally dropped but the presence of less than the total capacity of liquid in each envelope causes a surge when the package is dropped and this materially assists in avoiding accidental breakage and rupture.

As most hospitals have a glass or a metal container convenient and filled with a sterilizing liquid, any individual suture tubes which remain unused at the end of the operation may be readily dropped therewith to maintain the sterility of the outside of the tube. Thus those tubes and their contained sutures are still available for the next operation as spares.

While the invention has been described with particular reference to specific embodiments, it is to be understood that it is not to be limited thereto, but is to be construed broadly and restricted solely by the scope of the appended claim.

I claim:

A package comprising an outer, sealed, transparent flexible envelope containing a sterilizing liquid; and an inner, sealed, transparent flexible envelope, said inner envelope containing a sterilizing liquid; and a sealed container, said container having therein a suture the liquid in each envelope being less than its liquid capacity and each envelope being partially collapsed.
